UNITED STATES PATENT OFFICE.

FRANK CORKINS, OF ADAMS TOWNSHIP, LUCAS COUNTY, OHIO.

HEAD-REST.

942,485.

Specification of Letters Patent.

Patented Dec. 7, 1909.

Application filed September 29, 1909. Serial No. 520,113.

To all whom it may concern:

Be it known that I, FRANK CORKINS, a citizen of the United States, residing at Adams township, in the county of Lucas 5 and State of Ohio, have invented certain new and useful Improvements in Head-Rests; and I do hereby declare the following to be a full, clear, and exact description of the invention, such as will enable 10 others skilled in the art to which it appertains to make and use the same.

This invention has reference to improvements in head rests for chairs.

The invention is especially adapted for 15 use on barber chairs, although it may be applied to equal advantage on dental, invalid and other chairs where an adjustable and removable head rest may be required.

The object of the invention is to provide 20 a head rest of simple and inexpensive construction which may be adjusted to any of the usual positions required and which when not in use may be instantly swung out of the way without necessitating its removal.

25 In carrying out my invention I employ the novel combination, arrangement and the details of construction hereinafter shown, described and specifically pointed out in the claims.

30 In the accompanying drawings forming part of this specification in which like characters designate like parts throughout the several views, Figure 1 is a perspective view of my improved head rest applied to 35 the back of a chair. Fig. 2 is an elevation thereof, the parts in section being in the plane indicated by the line $x-x$, Fig. 3. Fig. 3 is a top plan view of the device, the stem which supports the pad or cushion 40 being in section, indicated by the line $y-y$, Fig. 2.

Referring to the drawings, 1 indicates 45 a main casting which is fixed to the chair back 2 near its upper margin. The casting is substantially channel shaped, having parallel sides 3 and 4 and an integral connecting rear portion 5, screws 6 being directed through the rear portion to securely fasten the same to the chair back. The sides 3 and 4 are each provided with an elongated 50 groove upon their inner faces as at 7 and 8, the grooves being directly opposite each other to provide a guideway for a sliding stem 9 which carries a pad or cushion 10 at 55 its upper end, the pad having a swinging adjustment about a screw 11 directed

through parallel lugs 12 and 13 and the stem 9, the lugs 12 and 13 being extended outwardly from a plate 14 secured to the under side of the pad 10 by screws 15. The 60 pad is held to any of the various positions which it may assume by a removable pin 16 directed through perforations in the lugs 12 and 13 and through one of a series of perforations 17 provided in the upper end 65 of the stem 9.

The stem 9 is provided on one side with a plain rib 18 and on the opposite side with a rib 19 formed with ratchet teeth adapted to be engaged by a spring pawl 20 pivoted between lugs cast integral with the side 4 of the casting 1, the pawl normally engaging the ratchet teeth and holding the sliding stem to any position to which it may be adjusted longitudinally. The pawl is disengaged from the teeth upon the stem by pressing upon the end 21. The stem 9 at its lower end is in the form of a hook 22 which traverses a slot 23 between the sides 3 and 4, the hook extending outward from said slot. 80

24 is a transverse pin secured between the upper ends of the sides 3 and 4 directly in the path of the hook 22, so that upon sliding the stem in an upward direction as indicated by dotted lines a , Fig. 2, the hook 22 85 will engage the transverse pin 24, and the stem 9 may then be swung upon the pin 24 as a pivot, as indicated by the arrows, and be suspended upon the pin out of the way in the position c . The sliding stem and 90 pad may be instantly restored to their original position by swinging the stem in a reverse direction to that indicated by the arrows, to the position a when the stem is in 95 position to be guided in the casting 1.

From the foregoing description, it is evident that I provide an adjustable head rest for chairs which is simple and inexpensive in construction and which may be instantly swung out of the way when not required for 100 use.

What I claim, is—

1. In a head rest for chairs, a longitudinally slotted main casting adapted to be fixed to a chair back, a pad-supporting-stem 105 slidably mounted in said casting and formed with a hook at its lower end adapted to traverse the slot in the main casting, and a transversely arranged stop fixed at the upper end of the main casting in the path of 110 the hook adapted to engage the hook and serve as a means for suspending the pad.

supporting-stem therefrom, substantially as described.

2. In a head rest for chairs, a main casting fixed to a chair back, having sides spaced 5 apart to provide a longitudinal slot, a pad-supporting-stem guided so as to slide in the main casting, the stem being formed at its lower end with a hook adapted to traverse the slot between the sides of the main casting, and a transverse pin supported upon the 10

main casting in the path of the hook upon the stem, substantially as described and for the purpose set forth.

In testimony whereof, I hereunto affix my signature, in presence of two witnesses.

FRANK CORKINS.
